HEATING DEVICE FOR HAIR TREATMENT.

Application filed September 25, 1925. Serial No. 53,490.

Our invention relates to devices for curling or otherwise forming hair into desired fashions.

The object of our invention is to provide 5 an improved construction with respect to the terminal contact parts of the electrically heated elements used for the purpose of heating and curling the hair in forming the so-called "permanent wave".

10 Our invention will be better understood by referring to the drawings which form a part of this specification.

Fig. 1 is a longitudinal view, partly in section, of a heating element, embodying our invention.

Fig. 2 is an end view taken on line 2—2 of Figure 1.

Fig. 3 is a cross-sectional view taken on line 3—3 of Figure 1.

20 Fig. 4 is an illustrational sectional view showing a metal ring imbedded and moulded in a covering of suitable insulating material and the construction of the contacting terminals for the wires carrying the heating 75 current.

Fig. 5 is a plan view of a modified construction, showing a metal ring with bushings of insulating material fixed therein to support the wire terminals.

30 Fig. 6 is a vertical sectional view through the ring shown in Figure 5, taken on line 6—6 thereof, and a sectional view of the cap portion of the device, with the screws to hold it to the ring.

Fig. 7 is a cross-sectional view of an insulated wire used as a heater in the device.

Fig. 8 is a view, partly in section, of one end of the insulation, and the wire therein, and illustrating how the wire is held in contact with a flattened band-portion used in 40 making the terminal contact portions. A indicates a thin metal tube of light material such as aluminium and provided with a handle A' of cork, felt, or other suitable heat-insulating material.

50 Mounted on the tube A in tight fitting relation thereto, is a metal ring B which is provided with two notches B' in its outer periphery located diametrically opposite to each other, and two notches B² in its inner periphery, also located diametrically opposite to each other, the notches B' and B² at each side of the ring being located adjacent to each other, as shown. The ring B is im- 55 bedded in a ring of insulating material C

which also fills the notches B' and B². Holes D—D—D—D respectively are formed in the insulation of the ring where it is located in the notches B' and B², to receive the flat band terminals E—E respectively, which 60 are connected directly with the ends of the round wire heating element F located in the asbestos covering F'.

The flat band terminal portion E is held 65 in contact with the round wire F by a circular band G at each end, which band is clamped tightly around the insulation F' and over the contacting ends of the terminal band E and wire F, as clearly illustrated in Figure 8. The flat band terminals E are 70 then passed through their respective holes D in one direction and are bent over and their free ends passed into the holes D respectively adjacent thereto in the opposite direction to form a hook which not only holds the ends 75 firmly in position, but permits the heating element to be drawn firmly in contact with the centre tube A, as will be readily understood.

The terminal conductor strips and the conductors have a lower electrical resistance than that of the heating element so that the heating element only, acts to generate heat.

An outer tube H is provided, one end of 85 which is reduced in diameter to fit in sliding engagement with the inner tube A, and its opposite end is made to fit over the outer periphery of the insulating ring C and is held in position by a screw I which passes through the tube H, and insulating ring C 90 and screws into the metal ring B, which in turn is secured to the centre tube A, thus making a complete unitary heating element.

A ring-shaped cap portion J is made to 95 slide over the tube A and is held to the ring B by two screws K, which extend through the cap and into the ring B, as shown. The cap is also provided with two holes M and M' for the conductors L—L respectively, which holes are located directly opposite to 100 and spaced from each other to correspond with the holes D—D. The hole M is large enough to receive the wire and covering of the conductor L, whereas the hole M' is large enough to receive the bare wire only, 105 which is bent into a hook form as illustrated, and is held in firm contact with the relatively wide band terminal E by the screws K—K, as will be readily understood.

In Figures 5 and 6 we have illustrated a 110

modified construction in which the metal ring B is not imbedded in insulating material but bushings N—N respectively are inserted in holes in the ring, and the tops of the bushings are flanged to provide a flat surface on which the flat band terminals E—E respectively may rest, the holes through the bushings serving the same function as the holes D—D serve in the construction shown in Figures 3 and 4.

By the construction above described a firm and durable device is provided that will give plenty of area of contacting surface between the round wire heating element and flat band terminal and with the round wire conductors L.

The construction also permits of easy assembling of the parts, and removes all danger of burning out at the points of contact of the terminals.

Having thus described our invention, we claim as new:

1. An electrical heating device comprising a tube, a ring mounted on said tube, insulating material carried by said ring and having holes therethrough, a terminal wire extending through one of said holes in one direction and into one of said holes adjacent thereto in the opposite direction to form a hook-shaped terminal.

2. An electrical heating device comprising a tube, a ring mounted on said tube, insulating material carried by said ring and having holes therethrough, a terminal wire having a flattened surface extending through one of said holes in one direction and into one of said holes adjacent thereto in the opposite direction to form a hook-shaped terminal.

40 3. An electrical heating device comprising a tube, a ring mounted on said tube, insulating material carried by said ring and having holes therethrough, a terminal wire having a flattened surface extending through one of said holes in one direction and into one of said holes adjacent thereto in the opposite direction to form a hook-shaped terminal, a conductor leading to said terminal and means for holding said conductor in overlying contact relation with said flattened surface.

45 4. A heating device comprising a central tube, a metal ring fixed on said tube, insulating material on said ring having holes therethrough, a heating element on said tube, a cap; conductors extending through said cap, and flat terminal bands extending through said holes in the ring to connect said conductors and said heating element together to provide an unbroken circuit.

50 5. A heating device comprising a central tube, a metal ring fixed on said tube, insulating material on said ring, a heating element on said tube, a cap, conductors extend-

ing through said cap, and flat terminal bands 65 extending through said ring which connect said conductors and said heating element together to provide an unbroken circuit, the ends of said bands and conductors being formed hook-shaped and means for holding 70 the cap to the ring.

6. A heating device comprising a central tube, a metal ring fixed on said tube, insulating material on said ring, a heating element on said tube comprising round wire 75 covered with asbestos, a cap, conductors extending through said cap, and flat terminal bands connected to said round wire and extending through said ring which connect said conductors and said heating element 80 together to provide an unbroken circuit, the ends of said bands and conductors being formed hook-shaped and means for holding said bands and conductors in proper fixed position between the cap and the ring, and 85 an outer tube carried by the centre tube and inclosing said heating element.

7. A heating device comprising a central tube, a metal ring fixed on said inclosing tube, insulating material on said ring, a heating element carried by said tube, terminal bands connected to the ends of said heating element and extending through said insulating material, a cap and conductors, the 90 ends of which are held in contact with said 95 terminal bands by said cap.

8. A heating device comprising a central tube, a ring of insulating material thereon, a heating element, terminals of lower electrical resistance than that of the heating element connected to the heating element and 100 extending through the ring and resting on the insulating material, a cap, conductors extending through the cap, the ends of which rest on the terminal elements in free separable relation thereto, and means for holding the cap to the ring.

9. An electrical heating device comprising a metal ring entirely inclosed in insulating material, and having holes leading therethrough, a cap connected to said ring by screws which extend through the cap and screw into the ring, a tube on which said ring and cap is mounted between its ends, a heating element carried on said tube, the 110 ends of which are provided with flat metal band portions which extend through said ring and rest on the top side thereof and are held between said ring and cap by said 115 screws; and electrical conductors extending through said cap and held in contact with said band conductors by said cap.

Signed at New York city in the county of New York and State of New York this 17th day of September, A. D. 1925.
